SINGLE KNOB OXIMETER HAVING SELECTIVE CONTROL MEANS FOR MULTIPLE CHANNELS

Glenn A. Millikan, Nashville, Tenn., assignor to
 United States of America as represented by the
 Secretary of War

Application April 4, 1947, Serial No. 739,456

9 Claims. (Cl. 88—14)

1

The invention described herein may be manufactured by or for the United States Government for governmental purposes without the payment to me of any royalty thereon.

The present invention relates to a single control compensated circuit oximeter, and also to an electrical control device which distinguishes the present oximeter from those commonly used.

The principal object of the invention is to provide a single knob electrical control means which simplifies the operation of a multi-channel oximeter and eliminates the chances of incorrect results due to errors in connecting the separate channel switches usually employed in multiple channel oximeters.

In my Patent No. 2,358,992, an oximeter is disclosed in the form of a single unit arrangement capable of handling one person at a time. As stated in the patent specification, it may be desired to test a number of persons simultaneously, in which case a multiple type oximeter may be used by mere duplication of the corresponding parts. This would however mean the duplication of switches and rheostats, or the like, and the completed apparatus would present a confusing array of controls which would require careful selection by the operator if uniform and expeditious tests were to be accomplished. Thus one object of the invention is the elimination of complicated controls in a multiple channel oximeter.

A related object of the invention is to provide a combined selector switch and potentiometer control device in which selection of a particular electrical circuit simultaneously effects accurate registration of a potentiometer control means and control switches which are a part of the circuit selected.

It is a further object of the invention to generally improve the construction and the operation of multiple channel oximeters.

The above and other objects of the invention will become apparent upon reading the following detailed description and claims in conjunction with the drawings, in which:

Fig. 1 shows a circuit diagram of a four-channel oximeter including the controls of the present invention and also showing a plan view of the selector and control switches;

Fig. 2 is a plan view of the oximeter control panel taken from the front side thereof;

Fig. 3 is a cross sectional view of the panel and associated control devices taken on the line 3—3 of Fig. 2, but omitting several potentiometers;

Fig. 4 is a plan view of a three-position control

2

switch forming part of the oximeter control, this view being taken from the rear side of the switch with the rear cover removed; and

Fig. 5 is a cross sectional view of the three-position switch taken on the line 5—5 of Fig. 4.

Referring to Fig. 1, the oximeter, or oxygen meter, includes four ear units 1a, 1b, 1c, and 1d, each of which may be constructed like the ear unit shown in Fig. 2 of the above-noted Patent Number 2,358,992. These ear units are substantially U-shaped in cross section so as to be adapted for fitting over the subject's ear and particularly for embracing the scapha membrane of the ear. Each ear unit includes an electric lamp 8a, 8b, 8c, or 8d, that is connected in parallel to a source of regulated voltage supply through a controlling switch 9. Each ear unit further includes a green-filtered photocell 10a, 10b, 10c, or 10d, and a red-filtered photocell 11a, 11b, 11c, or 11d, the green-filtered and red-filtered photocells of each ear unit having their ground terminals connected to a common lead 12a, 12b, 12c, or 12d, all of which in turn are connected to a single ground lead 13. Light from the electric lamp 25 may pass through the ear membrane to energize the corresponding red and green filtered photocells.

The photocells are arranged for connection to a sensitive galvanometer 14 by means of a selector switch 15 and a mechanically related control switch 16. It may be noted also that the selector switch 15 is equipped for making connection to six ear units even though the circuit as shown includes only four units. The selector switch 15 includes six upper contacts 17a to 17f, an upper arcuate shaped contact bar 18, six lower contacts 19a to 19f, a lower arcuate shaped contact bar 20, and an insulating brush bar 21 carrying wiper brushes 21a and 21b on opposite ends thereof. The insulating brush bar 21 is adapted to be rotated to allow the wiper brushes 21a or 21b to bridge the contacts 17a to 17f and the upper arcuate contact bar 18, or the contacts 19a to 19f and the lower arcuate contact bar 20. Each of the upper contacts 17a to 17d is connected to one of the red-filtered photocells 11a to 11d, respectively, through one of the potentiometers 22a to 22d, respectively; while each of the lower contacts 19a to 19d is connected to one of the green-filtered photocells 10a to 10d, respectively, through one of the potentiometers 23a to 23d, respectively, one terminal of each potentiometer being connected to the common photocell ground. The contacts 17a to 17f, contacts 19a to 19f, and arcuate contact bars 18 and 20 are

all mounted in a switch body of insulating material and may have connecting ears for soldering conductors thereto, as is well known in the art. The insulating brush bar 21 is non-rotatably secured to a shaft 24 for operating the selector switch as will be later described.

Referring to Figs. 1, 4, and 5, the three-position control switch 16 is shown having upper contacts 31, 32, and 33, an upper arcuate contact bar 34, lower contacts 35, 36, and 37, a lower arcuate contact bar 38, and an insulating brush bar 39 carrying spring contact brushes 40 and 41 on opposite ends thereof. The spring contact brushes 40 and 41, and the contacts 31 to 33 and 35 to 37 have interfitting portions to provide an impositive detent means. The insulating bar 39 is fixed to a shaft 42 that is rotatably mounted in an insulating switch case 43 that supports the contacts 31 to 33, contacts 35 to 37, contact bar 34, and contact bar 38. The contacts and contact bars have connectors for making soldered connections extending to the exterior of the switch case 43. The outer end of the shaft 42 has a bifurcated member 44 attached thereto for the purpose of actuating the control switch 16 to the position shown in Fig. 1 when the brush contact 21a of the selective switch 15 is operating across the upper arcuate contact bar 18, of actuating the insulating bar 39 to a vertical position when the selector switch brush contact 21a is between contacts 17a and 19f, and of actuating the control switch insulating bar 39 to a position diametrically in line with the contacts 33, 37 when the selector switch insulating bar 21 is rotated such that contact brush 21a is cooperating with the lower arcuate contact bar 20 in a manner later to be described. The spring contact brush 40 cooperates with contacts 31 to 33 inclusive for separately connecting one of these contacts with the upper arcuate contact bar 34; while the spring contact brush 41 cooperates with the lower arcuate contact bar 38 for electrically connecting the contact bar 38 with one of the contacts 35, 36, or 37.

The contacts 32 and 36 are connected together through a damping resistance 46 by a conductor 47. Contact 31 is connected to the upper arcuate contact bar 18 of the selector switch 15 by a conductor 48, and contact 35 is connected to the lower arcuate contact bar 20 of the selector switch 15 by the conductor 49. The contact 35 also connects the contact 33 through the resistance 50 by a conductor 51 and connects terminal 14a of the galvanometer 14 through an adjustable resistance 52 by a conductor 53. Contact 37 is connected to the common ground lead 13 of the photocells. The upper arcuate contact bar 34 is connected by the lead 54 to the terminal 14b of the galvanometer while the lower arcuate contact bar 38 is connected by the lead 55 to the galvanometer terminal 14a.

The galvanometer 14 has a single translucent scale 56 over which a spot of light is reflected from a deflection mirror receiving light from a light source as is well known in the galvanometer art. Connections for the light source of the galvanometer have not been shown since such a disclosure is not believed to be necessary for a clear understanding of the invention but this light source may be connected to the regulated voltage supply through switch 9 for convenience, if desirable.

The single control device for controlling the multi-circuit oximeter is shown more particularly in Figs. 2 and 3. In these figures there is shown

the oximeter control panel 61 having rotatably mounted thereon a control dial 62. The dial is secured on the outer end of the selector switch shaft 24, the switch itself being mounted on the panel 61 by nuts threaded on a central bushing which serves as a bearing for shaft 24. The shaft 24 includes a shoulder portion 24' against which the dial 62 is held by means of a cap nut 63. Thus rotation of the dial 62 by means of a knob 64 thereon effects movement of the insulating brush arm 21 of the selector switch 15 previously mentioned and a dial indicia 62' may be set opposite the channel or station Nos. 1 to 6 to select the corresponding contacts of the selector switch 15. The panel 61 carries besides the channel numbers the legends "Set filter" and "Saturation" to indicate which groups of contacts of the selector switch 15 are being selected in moving the dial. The "Off" position between the legends indicates that the wiper brush 21a is between contacts 17a and 19f, since the knob 64 is arranged in radial alignment with the brush contact 21a, and also indicates that the control switch 16 is turned "Off" in which the insulating brush arm 39 is diametrically in alignment with contacts 32 and 36.

The control panel carries upper and lower groups of potentiometers 22a to 22d, and 23a to 23d, corresponding to the potentiometers shown in Fig. 1, but including additional potentiometers for upper and lower stations or channels 5 and 6. Considering the potentiometer 22b in Fig. 3, it will be seen that the potentiometer bushing carries mounting nuts, and the bushing provides a bearing for a shaft 65 having a clutch disc 66 fixed on its outer end. The disc 66 is adapted to register with a disc 67 fixed on a knob shaft 68, which carries the single control knob 64. The clutch disc may be radially grooved for better driving action when engaged and it is also noted that a conical projection in the center of disc 66 is adapted to fit into a similar recess in disc 67 for more accurate registration of the discs. A coil spring 69 on the knob shaft 68 between the dial 62 and the knob 64 normally holds the disc 67 out of driving engagement with the potentiometer disc 66. The other potentiometers are each mounted on the panel in the manner shown in Fig. 2 and driven by the knob 64 in exactly the same manner as described above for the potentiometer 22b. It should be noted that locating the knob 64 and the dial indicia 62' at any one station or channel seeks a photocell section to the galvanometer and at the same time positions the knob 64 directly over the only potentiometer in the circuit that would require adjustment in such location.

The dial 62 also carries a control switch actuating pin 70 projecting within the space between the dial 62 and panel 61. The control switch 16 is mounted on the panel 61 with the bifurcated member 44 extending such that it is adapted to be engaged by the pin 70 to transmit rotary motion to the control switch insulating brush bar 39. As shown in Fig. 2 the dial 62 may be rotated to any one of the "Saturation" stations with the pin 70 disengaged from the bifurcated member 44 of the control switch 16 leaving the control switch in what will be later referred to as its "Saturation" position in which contacts 31, 34 and contacts 35, 38 are connected, but upon turning the dial 62 counterclockwise to the "Off" position the pin 70 will engage the bifurcated member 44 and rotate it clockwise about its shaft 42 until the shaft 42, member 44, pin 70, and

shaft 24 are in alignment in which contacts 32, 34 and 36, 38 are connected placing the damping resistance 46 across the galvanometer terminals. Further counterclockwise rotation of the dial 62 to any one of the "Set filter" stations will rotate the insulating brush bar 39 of the control switch approximately 45 degrees to what may be referred to as the control switch "Set filter" position in which it may be seen in Figs. 1 and 4 that the insulating brush bar 39 will be in diametrical alignment with the contacts 33 and 37. The impulsive detent construction of the control switch 16 retains this switch in any one of its three pre-selected positions until rotary motion is transmitted to it by the pin 70.

The operation of the selector switch, control switch, and potentiometers will now be described in greater detail in their relation to the ear units and galvanometer. The oximeter as shown diagrammatically in Fig. 1 is based on a colorimeter type of oxygen meter as disclosed quite fully in my patent previously identified. The patent is relied on for a discussion of the theory of the oximeter and its use in determining the percent of oxygen concentration in the blood, or a relative amount of oxyhemoglobin.

In the operation of the above described oximeter it is necessary for initially conditioning the device for use to properly adjust the variable resistor 52. The conductors 51 and 53 including the resistances 50 and 52 constitute an attenuating circuit for use in the standardization of the electrical and optical system in accordance with some selected standard filter in one of the ear units. The attenuating circuit may take the form of a single control potentiometer, if more desirable. In order to initially standardize this device for use let it be assumed that a standard .5A filter is used. With the main switch 9 in the "Off" position rotate the dial 62 to both No. 2 stations and adjust potentiometers 22b and 23b to the left stop in which case these potentiometers are short circuited. Snap on the main switch 9 and adjust the galvanometer spot by the regular galvanometer zero adjusting means until the spot rests at 89½. Place the .5A filter in the ear unit 7b and allow a few minutes for the ear unit to reach thermal equilibrium. Turn the dial 62 until the knob 64 comes to the "Set filter" No. 2 station and manually turn the control switch bifurcated member 46 back to its "Saturation" position, which is the position shown of this control switch in Fig. 2. Push the knob 64 in and rotate the potentiometer 23b until the galvanometer spot rests at 50 on the scale 56. This connects the green-filtered photocell 10b to the terminal 14a of the galvanometer 14 through the selector switch 15 and the control switch 16, the ground lead 12a being connected to the terminals 14b through the potentiometer 22b. Since the red-filtered photocell is short circuited any opposing voltage by the red-filtered photocell is eliminated. Further, the potentiometers for the green-filtered photocells are of much higher resistance than the corresponding red-filtered photocells such that complete control of photoelectric current furnished by any one of the green-filtered photocells is realized by the corresponding potentiometer 23. Manually turn the bifurcated member 46 to its "Set filter" position, wherein it will be in a position for engagement by the pin 70 upon the dial 62 being rotated to "Off" or "Saturation" positions. This connects only the green-filtered photocell 10b to the galvanometer 14 through the attenuating network

50, 51, 52, and 53, the red-filtered photocell being short circuited and its circuit to the galvanometer 14 being broken at contact 31. Adjust variable resistance 52 (which may be positioned behind the panel at any place though a bit inconvenient since this adjustment need be made only once unless future checks are desirable) until the galvanometer spot rests at 100. A standard resistance may be used in place of the variable resistance 52 if properly calibrated for the particular standard filters being used but use of a variable resistance is preferable for accurate adjustment. After the potentiometer 23b and the variable resistance 52 are adjusted as described above the dial should be rotated to the "Off" position and the galvanometer spot adjusted to rest at 50 on the scale 56 by the galvanometer scale zero adjusting means not shown herein since such adjusting means are common in galvanometer units. The purpose of the above described adjustments is to standardize the electrical and optical system such that the attenuating circuit has the bias ratio to give a deflection of the galvanometer spot to the left when the control switch 16 is in a "Saturation" position which is 2½ times the deflection of the spot to the right on the scale 56 when the control switch 16 is on "Set filter" position. This bias ratio should be 5 if an "A" filter is used. The attenuating circuit described above is merely for the purpose of standardization of the device by using the single scale 56 within the limits of 50 to 100 whereas in the absence of the attenuating circuit the scale would have to extend 2½ or 5 times to the left of 50 to arrive at such standardization. Since the above procedure of standardization need be made only once such conditioning of the device is not burdensome. The above operation may be made using any one of the ear units. With the above adjustments made and the standard filter still in place rotate the dial 62 in the "Set filter" direction until the indicia 62' rests at the station No. 2. This connects the green photocell 10b through the potentiometer 23b, contact 19b, brush 21a, bar 20, conductor 49, conductor 51, resistance 50, contact 33, brush 40, bar 34, and conductor 54 to the terminal 14b of the galvanometer. The other terminal 14a of the galvanometer is also connected through conductor 49, resistance 52, and conductor 53 to the green photocell 10b. The ground of the green photocell 10b is connected through the conductors 12b, and 13 to the contact 31, brush 41, bar 38, and conductor 55 to the galvanometer terminal 14a, the circuit through the resistance 52 being parallel to the circuit through the galvanometer 14. The circuit from the red-filtered photocell 11b is broken at the contact 31 of the control switch 16. The knob 64 is then depressed and the potentiometer 23b adjusted until the galvanometer spot rests at 100 on the scale 56. This provides full scale deflection of the galvanometer but with the proper ratio between the resistances 50 and 52 as formerly standardized. The dial 62 is then returned to the "Off" position and the standard filter replaced by the subject's ear. Where more than one subject is being tested the above procedure should be carried out for each ear unit. Using ear unit 7b for the purpose of illustration the dial 62 is again returned to the "Set filter" position for station No. 2. The ear should be allowed to warm up with the dial in this position. When the galvanometer spot 75 stops moving to the left, the ear is fully flushed

and an "ear reading" may be taken as a useful reference, if desirable.

The dial 62 may then be rotated in a clockwise direction to the "Saturation" position, station No. 2. Both red and green-filtered photocells 10b and 11b are now connected to the galvanometer 14 in opposition. The green-filtered photocell 10b is now connected to the terminal 14a of the galvanometer through the potentiometer 23b, contact 19b, brush 21b, bar 20, conductor 49, contact 35, brush 41, bar 38, and conductor 55; while the red-filtered photocell 11b is connected to the terminal 14b of the galvanometer 14 through the potentiometer 22b, contact 17b, brush 21a, bar 18, conductor 48, contact 31, brush 40, bar 34 and conductor 54. The knob 64 should be depressed and the potentiometer 22b adjusted to bring the galvanometer spot to 100 at any altitude below 30,000 feet if the subject is breathing pure oxygen (or 95 if the subject is breathing air at or near sea level). This is the "physiological setting" and any subsequent reading taken from the galvanometer 14 will indicate the per cent saturation of oxygen in the blood.

In the event the blood thickness of the subject's ear changes the difference in the photoelectric current from the green-filtered photocell 10b, compensates automatically for this change in blood thickness, in the manner in which manual adjustment was used in the aforementioned patent, to allow accurate saturation readings at all times.

As may be seen from the foregoing description any one of the six stations may be connected for testing per cent saturation of any one of six subjects merely by grasping the knob 64 and rotating the dial 62 to the desired station or channel. Any of the potentiometers 22a to 22d, and 23a to 23d, all inclusive, may be adjusted by simply depressing the knob 64 to bring the clutch discs 66 and 67 into engagement. The proper relation of the selector switch 15, control switch 16, and potentiometers is provided by operation of this single knob 64 which greatly simplifies an otherwise confusing operation. More than six subjects could be tested by such an oximeter device if additional contacts were constructed in the selector switch, and additional potentiometers and ear units added.

The embodiments of the invention herein shown and described are to be regarded as illustrations only and it is to be understood that the invention is susceptible to variations, modifications, and changes within the spirit and scope of the appended claims.

I claim:

1. A single control multiple channel oximeter comprising, a plurality of photocell units each including a photocell means and a light source and being adapted to receive a living membrane between the photocell means and the light source, each photocell means including a separate control potentiometer, a galvanometer adapted to be connected to each photocell unit to indicate the per cent of oxyhemoglobin in the blood of said living membrane, a selector switch for connecting only a single photocell unit to said galvanometer at a time, adjusting means connected to said selector switch and adapted to engage only one of said potentiometers at a time according to the position of the selector switch, and the electrical connections between the selector switch and photocell units including the connection of the potentiometers and the photocell means being such that selection of a particular photocell unit by

the selector switch thereby positions said adjusting means for engagement with the potentiometer connected to the photocell means included in said last mentioned photocell unit.

- 5 2. A single control multiple channel oximeter comprising a plurality of photocell units each including a green-filtered photocell, a red-filtered photocell, and a light source and being adapted to receive the living membrane of a subject between the photocells and the light source, each photocell being connected to a separate circuit each including a separate control potentiometer, a galvanometer adapted to be connected to each photocell unit through said separate circuits to 10 indicate for the green-filtered photocell the subject's ear type and for the red and green filtered photocells the subject's oxyhemoglobin percentage, a selector switch for connecting only a single photocell unit to said galvanometer at a time, 15 adjusting means connected to said selector switch and adapted to engage only one of said potentiometers at a time for operation thereof according to the position of said selector switch, and the electrical connections between said selector 20 switch and photocell units including the potentiometers and the respective red and green filtered photocells being such that positioning of said selector switch to obtain ear type indication or 25 oxyhemoglobin percentage indication thereby positions said adjusting means for engagement with the potentiometer connected to the green-filtered or the red-filtered photocell respectively, included in the selected photocell.
3. An oximeter as recited in claim 2 including, a control switch adapted for actuation by said selector switch and providing means to automatically connect any one of said green-filtered photocells to said galvanometer through an attenuating circuit through the respective separate circuit when said selector switch is actuated such that the adjusting means is in position to 35 adjust the potentiometer of said one of said green-filtered photocells, and to automatically connect both red and green filtered photocells of 40 any one of said photocell units to said galvanometer through the respective separate circuits when said selector switch is actuated such that said adjusting means is positioned to adjust the potentiometer of said red-filtered photocells of 45 said any one of said photocell units.

4. A control device for a multiple channel oximeter comprising, a channel selector dial mounted for rotation about a central axis, a selector switch actuated by rotation of said selector dial and including a plurality of pairs of switch contacts arranged arcuately about said central axis, each contact pair being adapted to connect corresponding red and green filtered photocells of a separate oximeter channel to an indicating instrument, a plurality of potentiometers arranged arcuately about said central axis, one each being in the connection of the red and green filtered photocells and being relatively stationary with respect to said selector dial, potentiometer control member mounted for rotation on said dial eccentrically thereof, said control member being adapted to register with actuating means on the respective potentiometers as said dial is rotated to select the respective pair of switch contacts for the respective red and green photocells, and the selection of a particular pair of red and green filtered photocells by said selector switch simultaneously bringing said control member into registration with the actuating means of a potentiometer which is adapted to control the photo-

electric current of the selected photocell of the pair.

5. A control device for a multiple channel oximeter comprising, a channel selector dial mounted for rotation about a central axis, a selector switch actuated by rotation of said selector dial and including a plurality of pairs of switch contacts arranged arcuately about said central axis, a plurality of pairs of potentiometers arranged arcuately about said central axis, each pair corresponding to a pair of switch contacts and being relatively stationary with respect to said selector dial, a potentiometer control and drive means eccentrically mounted on said dial, said control and drive means being adapted to register with actuating means on the respective potentiometer as said dial is rotated to select the respective pair of switch contacts, each pair of contacts providing selection of a separate oximeter channel and at the same time bringing said control and drive means into registration with the actuating means of one of the pair of potentiometers connected in the circuit of said separate oximeter channel.

6. A control device for multiple electrical circuits comprising, a circuit selector dial mounted for rotation about a central axis, a selector switch actuated by rotation of said selector dial and including a plurality of pairs of switch contacts arranged arcuately about said central axis, a plurality of pairs of potentiometers arranged arcuately about said central axis, each pair corresponding to a pair of switch contacts and being relatively stationary with respect to said selector dial, a potentiometer control and drive means eccentrically mounted on said dial, said control and drive means being adapted to register with actuating means on the respective potentiometers as said dial is rotated to select the respective pair of switch contacts, each pair of contacts providing selection of a separate electrical circuit and at the same time bringing said control and drive means into registration with the actuating means of one of the pair of potentiometers connected into said pair of separate electrical circuits.

7. An electrical control device comprising a se-

lector member mounted for movement and adapted to assume a plurality of separate positions, a selector switch controlled by the selector member and having a pair of contacts corresponding to each of said positions, a plurality of potentiometers which are relatively stationary with respect to said selector member, there being one potentiometer corresponding to each of said positions, a potentiometer control means mounted on said selector member and adapted for operative connection to the respective potentiometer one at a time as said selector member is moved to select the respective pair of switch contacts one at a time.

15 8. An electrical control device comprising a selector dial mounted for rotation about a central axis, a selector switch actuated by rotation of said selector dial and including a plurality of pairs of switch contacts arranged arcuately about said central axis, a plurality of pairs of potentiometers corresponding to said pairs of switch contacts arranged arcuately about said central axis and being relatively stationary with respect to said selector dial, a potentiometer control and drive means eccentrically mounted on said dial, and said control and drive means being adapted to make driving connection with the respective potentiometer one at a time as the dial is rotated to select the respective pair of switch contacts one at a time.

30 9. An electrical control device as recited in claim 8 wherein said pairs of switch contacts are arranged in two series together forming a circular array about said central axis, and including 35 a control switch adapted for actuation by said selector switch and providing means to automatically connect a source of electric current through one circuit including one of said potentiometers when said selector switch is connected to a pair 40 of contacts of one series and to automatically connect two sources of electric current of two separate circuits through both of the pair of said corresponding potentiometers when said selector switch is connected to a pair of contacts of the other series.

GLENN A. MILLIKAN.
